W. S. SMITH

WEIGHT HOLDER FOR SCALES

Filed March 28, 1925

Inventor

Walter S. Smith.

By W. S. McDowell.

Attorney

UNITED STATES PATENT OFFICE.

WALTER S. SMITH, OF COLUMBUS, OHIO.

DESIGN FOR A WEIGHT HOLDER FOR SCALES.

Application filed March 28, 1925. Serial No. 12,948. Term of patent 14 years.

To all whom it may concern:

Be it known that I, WALTER S. SMITH, a citizen of the United States, residing at Columbus, in the county of Franklin and State of Ohio, have invented a new, original, and ornamental Design for a Weight Holder for Scales, of which the following is a specification, reference being had to the accompanying drawing, forming part thereof.

The figure is a perspective view of a weight holder for scales showing my new design.

I claim:

The ornamental design for a weight holder for scales, as shown.

WALTER S. SMITH.
